UNITED STATES PATENT OFFICE.

EDWARD F. PARKS, OF PROVIDENCE, RHODE ISLAND, ASSIGNOR TO UNIVERSAL WINDING COMPANY, OF BOSTON, MASSACHUSETTS, A CORPORATION OF MASSACHUSETTS.

COP OR BOBBIN HOLDER.

1,340,978.

Specification of Letters Patent.

Patented May 25, 1920.

Application filed August 29, 1918. Serial No. 251,895.

To all whom it may concern:

Be it known that I, EDWARD F. PARKS, a citizen of the United States, residing at Providence, in the county of Providence, 5 State of Rhode Island, have invented certain new and useful Improvements in Cop or Bobbin Holders, of which the following is a specification.

My invention is an improved bobbin- or 10 cop-holder for use on winding machines and other textile apparatus. The object of my improvement is to provide means for holding different types of cops, bobbins or other yarn-supplies to adapt them for delivering 15 the material to winding, reeling or similar machines while allowing for more convenient application of the bobbins to the holder and greater facility in doffing the exhausted bobbins. To this end my invention consists 20 essentially of a holder or spindle which automatically grips the bobbin placed thereon, while at the same time positioning it in proper relation to the point to which the yarn is to be delivered; and one which is also 25 arranged to assume a more convenient position when the bobbin is withdrawn whereby to facilitate and expedite the application of a new bobbin thereto.

The manner and means for carrying out 30 these improvements are fully described in the following specification, illustrated by the accompanying drawings, in which like reference characters designate like parts.

In the drawings:—

35 Figure 1 is a side elevation of my improved cop-holder showing it in position to receive the cop or bobbin;

Fig. 2, a similar view, illustrating the bobbin held in place on the holder in position to deliver its yarn; and

Fig. 3, an end view of the cop-spindle showing the method of securing it to its base.

Referring to Figs. 1 and 2, 2 designates 45 a bracket or bearing-member which is adapted to be supported from any convenient part of the winding machine or other apparatus on which the device is used. As here shown the bracket 2 is formed with a curved arm or lug 3 adapted to be hooked 50 across a horizontal bar or rod 4 which forms a part of or is mounted on the machine

frame. A set-screw 5 extending transversely through the end of the lug 3 is provided with a pointed end arranged to impinge against the side of the rod 4 to clamp the bracket 2 in position thereon. On the opposite side of the bracket 2 is an extension or arm 6 which is cut away at its center or slotted at 7, as shown by the dotted line 60 in Fig. 1, to provide two spaced-apart ears 8. Extending downwardly from the bracket 2 is a flat plate or finger 9 formed integral with the arm 6 and employed for a purpose as later described. 65

Hingedly mounted on the bracket 2 is the cop-spindle or holder 10 which comprises the several parts as next described. The base or butt end of the holder 10 is preferably constructed in the form of a tapered 70 plug or cone 11 which is adapted to fit into the bore at the butt end of the bobbin B, see Fig. 2, to center the latter axially therewith. Projecting from the base of the conical plug 11 is a flat-sided tongue 12 which 75 is received in the slot 7, between the ears 8, 8 of the bracket 2, and pivoted thereto by means of a cross pin 13. Cut into one side of the plug 11 is a slot 14, see Fig. 3, which extends rearwardly from its smaller end to 80 a square shoulder 15, and is then continued through its base flush with the side of the tongue 12, see also Figs. 1 and 2. The squared end of the slot 14, that is the shoulder 15, is bored with a hole 16 which is 85 located axially of the plug 11.

Projecting from the end of the plug 11 is a tongs-like spring-member or split-spindle 17 which serves as the mandrel or skewer for the cop or bobbin B, see Fig. 2. 90 Preferably this element is constructed of half-round rod, bent back on itself at 18, see Fig. 1, to form a blunt-pointed tip, and extending in the two complementary halves or straddled legs 19 and 20. The main leg 95 19 has its end inserted in the axial bore 16 of the cone 11 and a short plug 21 of the same half-round shape in cross-section is driven in alongside it to fill the hole. Threaded through the side of the cone 11 100 is a set-screw 22 which is screwed against the leg 19 to bind it against the plug 21 to hold it in place in the bore 16. The opposite leg 20 of the spindle 17 extends in parallel

relation with the end of the main leg 19 for a short distance back from the tip 18 and is then bent laterally away therefrom to provide a V-shaped opening between the 5 parts, as shown in Fig. 1. At its rearward end the leg 20 is bent back at 23 angularly to its main portion and then straightened again in the offset length 24. When the two 10 legs 19 and 20 of the spindle or skewer 17 are sprung together, as shown in Fig. 2, their central portions will remain slightly bowed apart, owing to the inherent spring 15 tendency of the steel rod from which they are constructed. This provides that the 20 skewer 17 will exert a frictional grip against the sides of the bore *b* of the bobbin B when the latter is placed thereon, thereby serving as a retaining-means to prevent accidental removal. As the sides of the skewer are 25 contracted within the bore *b* of the bobbin B the angular extension 23 at the end of the leg 19 will slide into place within the slot 14 in the cone or plug 11, while its straight portion 24 will enter the slot 7 in the bracket 2. When the bobbin B is removed from the 30 skewer 17 the leg 19 is released and springs back to engage the end of its extension 24 with the vertical finger 9 on the bracket 2, whereby it acts as a catch or detent to hold the spindle in elevated position as illustrated in Fig. 1.

The method of operation of the complete device is as follows: My improved cop-holder is intended particularly for suspending the cop or bobbin in vertical, inverted position to adapt it to deliver its supply of 35 yarn to a point below. For this purpose the bracket 2 is attached to an overhead bar or rod 4 by hooking its lug 3 thereover and binding the set-screw 5 thereagainst. Fig. 1 illustrates the cop-spindle or skewer 17 in raised position with the end 24 of its expanding leg 20 bearing against the finger 9 on the bracket 2 to hold it at a convenient 40 angle to provide for placing the bobbin or cop thereon. The skewer 17 is adapted to receive cops or pirns wound on paper tubes, or any usual type of bobbin such as 45 shown in Fig. 2, the latter being wound on the wooden core or holder B. The bobbin B is applied to the skewer 17 by forcing it on to the pointed tip 18, and the spring-leg 20 will thereby be caused to contract against the leg 19 as the skewer enters the bore *b* of 50 the bobbin. The bobbin B is pushed onto the skewer until its base engages with the tapered plug 11 and the conical periphery of this element is designed to fit bobbins or tubes having bores of varying diameter so 55 that the device is universally adaptable as regards this feature. At the same time, the seating of the plug 11 in the end of the bore of the tube or bobbin serves to center the latter axially on the spindle. As the 60 two legs of the skewer 17 are brought to-

gether under the compression of the bobbin B their natural spring tendency causes them to be bowed outwardly slightly at the center to frictionally grip the interior of the bore *b*, as previously explained, and in 70 this manner the cop or bobbin is held securely in place to prevent accidental removal.

The contraction of the leg 20 of the skewer 17 releases its end from the finger 75 9 on the bracket 2 and causes it to be entered in the slot 14 in the plug 11. Now, as soon as the operator releases the bobbin the holder 10 will swing downwardly on its pivot 13, under the influence of gravity, 80 and the bobbin will assume a vertical position as shown in Fig. 2. In this way the cop-holder is automatically returned to its operative position immediately the bobbin is placed thereon, without the necessity of 85 releasing its catch or detent.

When the supply of yarn is exhausted the empty bobbin is removed or doffed from the holder by a single motion of the hand. The operator simply grasps the tube or empty 90 bobbin B and pulls it outwardly away from the bracket 2. This action causes the skewer or spindle 17 to be swung upwardly toward the horizontal, and as the bobbin is drawn off therefrom its leg 20 will spring back to 95 the position shown in Fig. 1 to engage its end with the vertical finger 9 on the bracket 2. This engagement causes the skewer 17 to be held in raised position so that a new 100 bobbin may be more conveniently slipped onto its end. As the new bobbin is applied the spring-leg 20 is retracted again to carry its end into the slot 14 in the plug 11, and the holder 10 is then free to drop into vertical position as shown in Fig. 2. In this 105 manner the device operates automatically to hold the cop-spindle raised to receive the bobbin and to return to operative position as soon as the bobbin is in place.

My improved device is designed particularly 110 for use on machines where space is limited or when it is required to place the yarn-supply in close relation to the point to which the yarn delivers. It is often impracticable to place the bobbin at sufficient 115 distance from the operating parts of the machine to allow for its removal from its spindle in line therewith. In such cases, by employing the present, improved device the bobbin may be drawn off at the side to clear 120 any obstructions which might prevent its withdrawal in another direction. At the same time this arrangement for swinging the bobbin-holder to the side provides for greater convenience in withdrawing the 125 bobbin toward the operator and clearing it from the machine below. A further improved feature of the device is the automatic operation of the detent-means which acts upon the removal of the bobbin to hold 130

the spindle in raised position, and immediately upon the application of a new bobbin releases it to allow it to return to its operative position. It will be observed that the 5 bobbin-holder cannot remain out of its delivery position as long as a bobbin is in place on the spindle, but must return thereto after being drawn aside for any purpose. That is to say, the operator may draw the 10 bobbin to one side or raise it for the sake of convenience in piecing up a broken yarn, but upon its release it will automatically return to its position of delivery. When, however, the bobbin is doffed, the cop-holder 15 remains in its raised position to facilitate the application of a fresh bobbin to the spindle, and in this way considerable time and energy is saved on the part of the operator and the whole operation of the machine is expedited.

My improved device is extremely simple in construction, economical to manufacture and proof against derangement or getting out of order. It may be used to advantage 25 on various and sundry types of textile apparatus and is universally adaptable to practically all forms of cops or bobbins. Various modifications might be made in the construction and arrangement of the parts 30 of the device without departing from the spirit or scope of the invention; therefore, without limiting myself to the exact embodiment herein shown and described, what I claim is:—

35 1. The combination with a tilting bobbin-holder, of means for engaging the bobbin to secure it in place on the holder, said means adapted to maintain the holder in its tilted position when the bobbin is removed therefrom and to release the holder to allow it to return to normal position when another bobbin is placed thereon.

40 2. In a supply-holder for textile machines, the combination with a tilting bobbin-holder, 45 of means for engaging the bore of the bobbin to secure the latter in place on the holder, said means adapted to maintain the holder in tilted position when withdrawn from the bore of the bobbin and to release the holder 50 when a new bobbin is engaged therewith.

3. In a supply-holder for textile machines, the combination with a spindle for receiving the bobbin, of means for suspending the spindle in vertical position to allow it to tilt 55 on a horizontal axis, and means engageable with the bobbin to secure it in place on the spindle, said means adapted to maintain the spindle in tilted position when released from engagement with the bobbin.

60 4. In a supply-holder for textile machines, the combination with a bracket, of a bobbin-spindle hinged to the bracket to suspend it in vertical position therefrom, and means on the spindle for engaging the bobbin to hold 65 it in place thereon, said means adapted to

engage the bracket when released from the bobbin to hold the spindle in tilted position to facilitate the placing of a new bobbin thereon.

5. In a supply-holder for textile machines, 70 the combination with a tilting bobbin-spindle, of a spring-member for engaging the bobbin with the spindle to secure it in place thereon, said member adapted to maintain the spindle in tilted position when disengaged from the bobbin and to release the spindle to allow it to return to normal position when another bobbin is applied thereto.

6. In a supply-holder for textile machines, 75 the combination with a bracket adapted to be fastened to the machine frame, of a spindle mounted on said bracket to adapt it to be supported in substantially vertical position and to tilt on a horizontal axis, and a spring-member on the spindle for frictionally engaging the bobbin to secure it in place thereon, said spring-member adapted when released from the bobbin to spring into position to engage the bracket to hold the spindle in tilted position.

90 7. In a supply-holder for textile machines, the combination with a bracket, of a spindle hinged to the bracket to adapt it to tilt thereon, and a spring-member extending longitudinally of the spindle in divergent spaced relation therewith to adapt its end to spring away from the spindle to engage with the bracket to maintain the spindle in tilted position.

95 8. In a supply-holder for textile machines, 100 the combination with a bracket, of a bobbin-spindle hinged thereto to adapt it to tilt thereon, said spindle split longitudinally to provide a spring-member for engagement with the bore of the bobbin, and said spring-member also adapted to spring away from the spindle to engage its end with the bracket when released from the bobbin to hold the spindle in tilted position.

105 9. In a bobbin-holder for textile machines, 110 the combination with a bracket, of a conical plug hinged to said bracket and adapted to enter the bore of a bobbin to center the latter thereon, and a bobbin-spindle extending from the plug in axial relation therewith, 115 said spindle formed with two divergent legs connected together at the outer end with the inner end of one leg secured to the plug and the opposite leg extended away therefrom to adapt it to engage with the bracket to hold the spindle in tilted position.

120 10. In a bobbin-holder for textile machines, the combination with a bracket formed with a projecting finger, of a spindle hinged to said bracket and formed with 125 two divergent legs connected at their outer ends and having the inner free end of one leg sprung away from the other leg to adapt it to engage with the finger on the bracket to hold the spindle in tilted position.

11. In a supply-holder for textile machines, the combination with a bracket, of a conical plug hinged to said bracket and provided with a slot in its side, of a bobbin-skewer formed with two divergent legs connected at their outer ends with the inner end of one leg secured to the end of the plug and the free end of the opposite leg sprung away from the plug but adapted to be contracted within the slot in its side.
12. In a supply-holder for textile machines, the combination with a bracket

formed with spaced-apart ears, of a conical plug having a tongue hinged between the ears on the bracket, and a bobbin-skewer 15 projecting from the end of the plug and provided with a divergent spring-leg extending rearwardly from its tip with its free end bent away from the plug to adapt it to engage the bracket to maintain the skewer in 20 tilted position.

In testimony whereof I affix my signature.

EDWARD F. PARKS.
